UNITED STATES PATENT OFFICE.

MAXWELL L. ROSE, OF LOS ANGELES, CALIFORNIA.

SHOE-LACE TIP.

Application filed June 23, 1925. Serial No. 39,019.

My invention is a shoe lace tip in which a detachable tip is secured to the end of a shoe lace. This construction is preferable by having a suitable permanent tip of the lace which may be inserted through the eyelets in the shoe and having the permanent tip so constructed as to engage and hold the detachable tip.

An object of my invention is thus to provide a detachable tip which, after lace has been threaded through the eyelets of a shoe, may have the detachable tip secured thereon, which tip is of sufficient size to prevent the lace unlacing through the eyelets. Therefore, when a lace has been threaded into the eyelets in the shoe with the detachable tip secured at each end, the lace will not become unthreaded unless the secondary tip is detached. The tips may be made of ornamental metal such as various colors of glass, celluloid or the like and provide an effective ornament for the shoe lace. As these detachable tips are inexpensive and readily secured and removed from the permanent tip, a person may have a variety of colors to match different shades of stockings or socks.

I may make the permanent tip in a variety of forms and secure the detachable tip thereto in many different ways; for instance, the permanent tip may be screw threaded on the outside and the secondary tip threaded thereon. The screw threading on the permanent tip may be formed at the time a sheet metal tip is pressed on the end of the shoe lace fabric. In one form, I provide a sheet metal permanent tip with a series of prongs pressed inwardly to engage the shoe lace and with the threads pressed on the outside. In another form the permanent tip may have a slightly bulbous shape or annular ring and the detachable tip have spring actuated prongs to be attached thereto by sliding motion.

My invention will be more readily understood from the following description and drawings, in which;

Figure 1 is a perspective view of the shoe, showing my detachable tip applied to a shoe lace.

Fig. 2 is a detailed sectional view of one form of tip showing the fabric of the lace being secured to a screw threaded pin, the

end of the pin forming the connection with the detachable tip. 55

Fig. 3 is another modification of the tip, showing a pressed metal permanent tip which holds the shoe lace and has threads pressed in the surfaces thereof to hold the secondary tip in position. 60

Fig. 4 is a further detail showing the permanent tip and the detachable tip engaged by a straight sliding motion in the manner of dome or button fasteners.

Fig. 5 is a further detail showing a sheet metal permanent tip with prongs pressed inwardly in the operation of securing the tip to a lace and having screw threads pressed into the surface. 65

Fig. 6 is a cross section on the line 6—6 of Fig. 5. 70

Fig. 7 is a detail of a form of tip in which a bead is secured to the end of a lace having a reduced permanent point and held thereon by glue or cement. 75

In Fig. 1, a shoe 1, having eyelets, has a lace 3 threaded through the eyelets. The lace shown is fastened by a bow knot 4 and has a pair of detachable tips 5, secured on the permanent tips which are thus covered. The detachable tip 5 is of larger diameter than the eye, so that the lace will not become unthreaded when the bow is untied either accidentally or purposely. 80

Referring to Fig. 2, the lace 3 has a permanent tip 6, formed of a screw threaded pin 6' to which the fabric of the lace is secured at the upper end of the pin as indicated at 7, by cementing, glueing or the like. The detachable tip 5, has a recess 8 at the upper end and a screw threaded socket 9 to be threaded on the lower end of the pin 6'; thus in this construction the detachable tip is readily secured to the permanent tip and does not rub or wear the fabric of the lace. 85

In Fig. 3, the lace 3 is pressed into the permanent tip 6, which is preferably constructed of a sheet metal cylinder 10, having screw threads 11 pressed into the surface thereof. This represents a common type of tip, except for the screw threads which are not required in the ordinary tip. This permanent tip will be secured in the same manner as those now on the market, the exterior surfaces having screw threads. The detach- 100 105

able tip 5 is shown screw threaded and having a screw threaded socket 12 extending from its upper end deep into the body of the detachable tip. This tip may readily be secured to the permanent tip by screw threading thereon.

In Fig. 4, the lace 3 has a permanent tip 6 secured thereon, such tip being formed of a metal socket 13 pressed or cemented thereon, the socket being shown with the bulbous section 14 forming an annular ring.

The detachable tip 5 has a socket 15 formed of slightly split fingers 16 with an outwardly curved section 17 to conform to the ring 14. This type of tip is placed on the permanent tip by directly pressing thereon, and is held in place by the spring action of the fingers 16. This construction could be reversed in which the permanent tip 6 will be made of spring metal having slits therein to allow the bulbous section 14 to press inwardly and the detachable tip could be formed of the same character as the dome of the so-called dome or button fasteners, the tips being secured together by pressing in a longitudinal direction and removed by pulling.

Fig. 5 shows a sheet metal permanent tip 6, secured to the lace 3 by pressing and has a series of angular cuts forming prongs 18, these prongs are pressed into the fabric of the lace and hold it in position. Threads 19 are pressed into the surface of this lace, much in the same manner as described in connection with Fig. 3, and the detachable tip 5 has a screw threaded socket 20 to conform to the threads on the tip.

Fig. 7 is a further modification in which a substantially permanent character of enlarged tip is employed. The lace 3 is illustrated with a reduced and pressed point 21 formed of the type having glue, cement or the like embedded in the fabric of the lace and pressed to such a diameter as to be readily threadable through an eyelet. A bead 22 has an aperture 23 therethrough of such diameter as to be readily threaded over the point 21. In this construction the bead or the tip would preferably be provided with a glue or cement end and which would soften under heat, or a small amount of glue could be applied to the point or the aperture 23 so that when the point is drawn through the bead these will become substantially permanently connected, forming an enlarged tip on the lace.

It will be apparent that the type of fastening used between the permanent tip and the detachable tip may be materially changed. In many cases it is not desired to remove the lace from the shoe until worn out or shabby and therefore the permanent tip may be secured in such a manner as to have a substantially permanent connection. In many of the tips 2 to 5 a cement or glue

could be utilized to make the connection between the permanent tip and the secondary tip substantially permanent. It will be obvious that the cemented type of permanent lace tip could be used and that a somewhat sticky material could be utilized so that by application of a slight heat for the attachment of the attachable tip, would secure these together in a substantially permanent manner after the lace has been threaded through the shoe eyelets.

Many other applications of the enlarged tip will be apparent where it is desired to thread a lace through a series of eyelets and then secure a device at the end of the lace to prevent unlacing thereof.

Having described my invention, what I claim is:

1. A lace tip comprising in combination a lace, said lace having a permanent end of small diameter adapted to thread through an eyelet and a tip attached directly thereto of sufficient diameter to prevent withdrawing the lace from the eyelet, said tip being attached after threading of the small permanent end through an eyelet.

2. A lace tip comprising in combination a lace, a permanent tip secured thereto of such diameter as to be readily threaded through an eyelet and an attachable or detachable tip secured directly to the permanent tip of such diameter as to prevent removal through an eyelet, said attachable and detachable tip being secured to the permanent tip after same has been threaded through an eyelet.

3. A lace tip comprising in combination a lace, a permanent tip secured to the outside of said lace and compressing the lace to a diameter suitable for readily threading through an eyelet and an attachable and detachable tip secured directly to the permanent tip and being of such diameter, as to prevent threading through an eyelet, said attachable and detachable tip being secured to the permanent tip after same has been threaded through an eyelet.

4. A lace tip as claimed in claim 3, in which the permanent tip and the attachable and detachable tip have a screw threaded connection.

5. A lace tip comprising in combination a lace, a permanent tip secured to the end and the outside of the lace, said tip compressing the lace whereby the tip and the lace may be readily threaded through an eyelet, a detachable tip having a body portion of larger diameter than the eyelet and having a socket extending deeply into the body, said permanent tip and socket having co-acting means to secure one to the other.

6. A lace tip as claimed in claim 5, in which the socket and the permanent tip are connected by screw threads on the tip and in the socket.

7. A lace tip comprising in combination a

shoe lace, a permanent sheet metal tip secured thereto, said tip having prongs pressed inwardly to engage the material of the lace and having screw threads pressed in the sheet metal, and an attachable and detachable tip comprising a body portion of sufficient diameter to prevent passing through

an eyelet and having a socket with screw threads to engage the threads of a permanent tip.

10

In testimony whereof I have signed my name to this specification.

MAXWELL L. ROSE.
